SUSPENSION DEVICE

William White, Flint, Mich.

Application December 23, 1938, Serial No. 247,449

1 Claim. (Cl. 24—137)

This invention relates to a suspension device designed primarily for suspending clothes from a clothes line, but it is to be understood, that a suspension device, in accordance with this invention is for use in any connection for which it may be found applicable.

The invention aims to provide, in a manner as hereinafter set forth, a device of the class referred to for suspending wet garments, sheets, towels etc., indirectly from a clothes line for the purpose of drying them without the wrapping thereof around the line thereby overcoming the objection of the garments freezing to the line in the winter.

The invention further aims to provide, in a manner as hereinafter set forth, a suspension device including a pair of oppositely disposed spring controlled quickly releasable clamps of like-form connected together by the controlling springs therefor in inner lengthwise edge abutting engagement, and one for clamping on a hanger in suspended relation thereto and the other for clamping to and suspending an object free of direct connection to the hanger.

The invention further aims to provide, in a manner as hereinafter set forth, a suspension device for the purpose referred to which is simple in its construction and arrangement, strong, durable, compact, conveniently operated to clamping and suspension position, readily assembled, thoroughly efficient in its use and comparatively inexpensive to manufacture.

Embodying the foregoing aims and others which may hereinafter appear, the invention consists of the novel construction, combination and arrangement of parts as will be more specifically described and illustrated in the accompanying drawing, wherein is shown an embodiment of the invention, but it is to be understood that changes, variations and modifications may be resorted to which fall within the scope of the invention as claimed.

In the drawing:

Figure 1 is an elevation looking towards one side of the device,

Figure 2 is an elevation looking towards the rear lengthwise edge of the device,

Figure 3 is an exploded view in side elevation of the form of the pair of clamping members of each of the clamps,

Figure 4 is a side elevation of one of the clamps of the device disposed horizontally,

Figure 5 is an elevation of the form of controlling spring employed in each of the clamps, and

Figure 6 is an elevation of a modified arrangement of the parts of the device in side elevation.

The device includes a pair of oppositely disposed inner lengthwise edge abutting clamps 6, 7 of like form.

Each of said clamps include a pair of oppositely disposed coacting clamping members 8, 9 being formed from bars of uniform length and width as indicated at 10, 11 respectively (Figure 3). The outer lengthwise edge 12 of the bar 10 is straight and flat and between its transverse median and its end 13 is formed with a transverse groove 14. The other end of the bar 10 is indicated at 14a. The bar 10 is formed with oppositely disposed tapered end terminal portions 15, 16. The portion 15 is of greater length and of less thickness than the portion 16. The bar 10 is formed with a pair of oppositely disposed intermediate tapered portions 17, 18 and a tapered portion 19. The portion 17 is of greater length than the portion 18. The portion 19 is of greater length than the portion 18. The portion 17 extends from the portion 15. The portion 19 extends from the portion 16 and merges into the portion 18. The portion 15 gradually decreases in thickness towards the portion 17. The portion 16 gradually decreases in thickness towards the portion 19. The latter is of greater thickness than the portion 16. The bar 10 includes a substantially central portion 20 into which the portions 17, 18 merge. The portion 17 gradually decreases in thickness towards the portion 20. The latter has its inner edge 21 of semi-circular contour. Between the portions 15 and 17, the bar 10 is formed with a transverse groove 22. The edge 23 of portion 15 inclines inwardly from its outer end to the groove 22. The edge 24 of the portion 17 inclines inwardly from groove 22 to the edge 21 of portion 20. The edge 25 of portion 18 inclines inwardly from portion 19 to the edge 26 of portion 20. The edge 26 of portion 19 inclines outwardly from its outer end to the edge 25. The edge 27 of portion 16 inclines inwardly from its outer end to the portion 19.

The bar 11 has its outer lengthwise edge 28 straight and smooth and it is formed between its lengthwise median and end 29 of bar 11 with a transversely extending rectangular notch 30. The bar 11 is formed with end terminal portions 31, 32 of tapered form and oppositely disposed. The bar 11 is also formed with tapered portions 33, 34, 35 and 36. The portion 31 is of greater length and of less thickness than the portion 33. The portion 34 is of less length than the portion 33. The portion 35 is of less length than the portion 34. The portion 36 is of greater length than the portion 35 and the portion 32 is of greater

length than the portion 36. The portion 32 is of greater thickness than the portion 31 and of greater thickness than the portions 35, 36. The bar 11 includes a substantially central portion 37 having its inner edge 38 of substantially semi-circular contour. The portion 31 merges into the portion 33, the latter merges into the portion 37, the portion 34 merges into the portion 37, the portion 35 merges into the portion 34, the portion 36 merges into the portion 35 and the portion 32 merges into the portion 36. It may be stated that the portion 32 is substantially of triangular contour and this statement applies to the other portions of the bar 11 and also to the portions of the bar 10. The bar 11 has its inner lengthwise edge formed with inwardly inclined edge portions 39, 43, 41, 42 and 43 and outwardly inclined edge portions 44, 45. The edge portion 39 extends from the end of member 11 to the edge portion 49. The latter extends from the edge portion 39 to the semi-circular edge 38. The edge portion 43 extends from the end 29 of bar 11 to the edge portion 45. The latter merges into the edge portion 42, the edge portion 42 merges into the edge portion 44 and the latter merges into the edge portion 41. The edge portion 41 merges into the semi-circular edge portion 38. The edge portions 23, 39 align with each other. The edge portions 24, 49 align with each other, the edge portions 20, 38 align with each other and the edge portion 25 aligns with the edge portion 41. The latter is of greater length than the edge portion 25. The edge portions 42, 44, also the edge portion 26 and the edge portion 45 substantially aligns with a horizontally disposed edge portion 46 on the member 10. The edge portions 27, 43 align. Mounted in the edge portions 21, 38 is the coiled body 47 of a controlling spring 48 for the bars 10, 11. The length of body 47 is greater than the width of the bars. The ends of the spring 48, indicated at 49, 50 are extended. The said ends 49, 50 are of angle form and oppositely disposed. The end 49 includes a leg 51 and a leg 52. The latter is disposed in parallelism to the body 47. The leg 52 extends inwardly at right angles to the leg 51. The end 50 includes a leg 53 and a leg 54 extending inwardly at right angles to the leg 53 and arranged parallel to the body 47. The leg 52 is of greater length than the leg 54. The ends 49, 50 of the spring 48 extend in opposite directions with respect to each other. When the bars of the clamps are connected together and the clamps connected together in abutting engagement the leg 53 of the end 50 of the spring 48, which forms an element of clamp 6 extends across the bar 11, the leg 54 seats in the notch 30 on the outer lengthwise edge of the latter, the leg 51 of the end 49 of the spring 48, which forms an element of clamp 6 extends across bar 10 of clamp 6 and bar 10 of clamp 7 and leg 52 of spring end 49 seats in groove 22. The spring 48 which forms an element of clamp 7 has its end 49 connecting bars 10 of the clamps in abutting engagement and its end 50 engaging with the bar 11 of clamp 7 in the same manner as the end of the spring of clamp 6 engages with the bar 11 of clamp 6. The arrangement of the springs 48 relative to the clamps 6, 7 are as shown in Figure 1 and such arrangement provides for the bars 11 to be spring controlled and the bars 10 connected together in abutting arrangement.

When the clamps 6, 7 are coupled together by the springs 48 they are oppositely disposed and each may be selectively employed for clamping to the line or for clamping the clothes thereto. The clamp which is to be connected to the line will be disposed in a manner in what may be termed an upwardly disposed arrangement and the other clamp in what may be termed a downwardly disposed arrangement. When the clamps 6, 7 are connected together, the springs 48 align. The bars 11 of the clamps are movable relative to the bars 10 thereof.

The edge portions 41, 44 of bar 11 and edge portion 25 and a part of edge portion 26 of bar 10 coact to provide an opening 55 for the passage of a line or hanger or for the extending therein of the article to be suspended. The edge portions 42, 45 and 43 of the bar 11 coact with the edge portions 46, 37 and 26 of the bar 10 to provide gripping means whereby the article may be suspended by a clamp and with such edge portions gripping the article. If a clamp 6 is used the line or hanger will be passed through opening 55 and the edge portions 43, 45, 42, 27, 46 and 26 of clamp 7 will be employed with the gripping means.

The groove 14 of each clamp is provided for receiving the leg 52 of the end 49 of the spring 48 of a clamp when the clamps are disconnected from each other.

The bars 10 are termed the inner bars of the clamps. The bars 11 are termed the outer bars of the clamps. The body portions 47 of the springs 48 form pivots or fulcrums for said outer bars. That clamp which is connected to the clothes line may be termed a hanger and the other clamp a suspender.

With reference to Figure 1 the bars 11 are disposed outwardly of the bars 10. These latter are clamped in abutting relation throughout by the springs 48, but with reference to Figure 6 the bars 10 are disposed outwardly of the bars 11 and these latter are clamped in abutting relation throughout by the springs 48.

What I claim is:

In a suspension device, a pair of oppositely disposed clamps disposed in fixed inner sidewise abutting relation throughout and each formed of an inner clamping bar, an outer clamping bar and a controlling spring having a coiled body arranged between and seated in said bars, said bodies at one termini thereof having oppositely disposed extended end portions overlapping and slidably mounted in the outer edges of the outer bars of the clamps for spring-controlling such bars and for coupling them to said bodies, said bodies at the other end termini thereof having oppositely disposed extended end portions overlapping and fixed in the inner edges of the inner bars of the clamps for maintaining the outer side edges of said inner bars in fixed abutting relation throughout, each of said clamps having the inner edges of its bars provided with coacting parts bordering and coacting with the body of its spring to form means therein for selectively mounting a clamp on a hanger, and each of said clamps having the inner edges of its bars formed with other coacting parts outwardly adjacent to the said means of the clamp for suspending an article.

WILLIAM WHITE.
